No. 781,403.

PATENTED JAN. 31, 1905.

G. H. & C. H. W. CLIFF.
DISPLAY BOX.
APPLICATION FILED SEPT. 2, 1904.

UNITED STATES PATENT OFFICE.

GEORGE H. CLIFF AND CHARLES H. W. CLIFF, OF PHILADELPHIA,
PENNSYLVANIA.

DISPLAY-BOX.

SPECIFICATION forming part of Letters Patent No. 781,403, dated January 31, 1905.

Application filed September 2, 1904. Serial No. 223,095.

To all whom it may concern:

Be it known that we, GEORGE H. CLIFF and CHARLES H. W. CLIFF, citizens of the United States, residing in the city and county of Philadelphia, State of Pennsylvania, have invented a new and useful Display-Box, of which the following is a specification.

Our invention consists of a display-box having a plate adapted as a sign or indicator for the contents of the box, a transparent plate through which said contents may be seen and inspected, and novel means for holding said plates in position and permitting the ready removal of the same, as will be hereinafter described, the novel features being pointed out in the claims.

It also consists of details of construction, as will be hereinafter described.

Figure 1 represents a perspective view of a display box or can embodying our invention. Fig. 2 represents a vertical section thereof on line xx , Fig. 1. Fig. 3 represents a vertical section on line yy , Fig. 1. Fig. 4 represents a perspective view of a portion of the interior 25 of the box or can.

Similar letters of reference indicate corresponding parts in the figures.

Referring to the drawings, A designates a receptacle, preferably made of metal, after the order of a tin can and comprising a display-box which is provided with a lid and having a plurality of openings B C in its front wall. The top of the box has a flange or rim D, in which is a vertically and transversely extending recess or passage E, the same leading into the interior of the box. Secured to the side walls of the receptacle, on the interior thereof, are vertically-extending strips F, which inwardly overlap the side edges of the front wall of the box and are separated from said wall, forming passages G, which are open at top and bottom for purposes to be hereinafter explained.

H designates the member for closing the upper opening B, the same consisting of a plate of metal or other rigid and opaque material, which is located in the box at the rear of said opening B.

J designates the member for closing the

lower opening C, the same consisting of a piece or pane of glass or other transparent material, which is located in the box at the rear of said opening C, said plate and piece forming in a measure a vertical continuity of each other. Formed with or secured to said plate and depending therefrom are ears K, which are adapted to embrace the upper end of the piece J for interlocking the contiguous ends of the plate and piece and preventing rear displacement of the upper portion of said piece.

Rising from the bottom of the box, immediately at the rear of the front wall thereof, is the lip L, forming, with said wall, the vertical passage M, in which is received the lower end 65 of the piece J, whereby said end is controlled against rearward or inward displacement.

In assembling the parts the piece J is introduced into the box and seated in the passage M. The plate H is also introduced into the box and lowered below the strips F, after which its upper end is guided and introduced into the passage G. The plate is then raised, the strips F acting as guides therefor, it being noticed that said strips are of less height 75 than said plate H. As the plate rises its upper end is not restrained, but slides through the passage E in the top of the box. When the ears K have cleared the top edge of the piece J, the plate is lowered and said ears are 80 fitted over the top edge of the piece J, thus taking hold of said edge and interlocking the plate and piece and retaining them in operative position, this being assisted by the strips or guides F and lip L and the front wall of the 85 box, as will be most apparent in Fig. 3. It will be also seen that the plate H may have the name of the contents of the box, manufacturer thereof, &c., displayed thereon, and the piece J permits the nature of the contents to be seen 90 and inspected from without, it being also seen that if the contents only reach the top line of the opening J the box does not expose the half or partly full condition of the box, but presents all of the appearance of a full box, 95 while being sufficient for display purposes. It will also be noticed that the strips F, the ears K, and the lip L are concealed, and so do

not disfigure the front of the box. In order to remove the plate H and piece J, said plate is raised so as to withdraw the ears k from said piece. Then the piece may be raised and withdrawn through the top of the box. The plate is now lowered until it clears the guides F, when it may also be raised and withdrawn from the box. It is evident that the means employed for holding the plate and piece in the box and permitting the removal thereof are simple, inexpensive, and practical, it being noticed that the ears K are fixed members of the plate H, and so are easily constructed, preferably integral with said plate, and possess strength and durability, and as they embrace the opposite sides of the glass piece or plate A both members remain interlocked as one and either member is prevented from moving backwardly or inwardly.

20 Various changes may be made in the details of construction shown, and we do not, therefore, desire to be limited in each case to the same.

Having thus described our invention, what we claim as new, and desire to secure by Letters Patent, is—

1. A display-box provided with a plurality of openings in a wall thereof, an indicating-plate adapted to close one of said openings, a transparent piece adapted to close the other opening and means intermediate of the adjacent edges of said plate and piece for interlocking the same, said means consisting of ears fixed to the edge of said indicating-plate and adapted to embrace the adjacent edge of said transparent piece.

2. A display-box provided with a plurality of openings in a wall thereof, an indicating-

plate, a transparent piece adapted to close said openings respectively, means intermediate of the adjacent edges of said plate and piece for interlocking the same, and a passage in the upper portion of the box through which said indicating-plate may be elevated for separating said interlocking means, said means consisting of ears depending from the edge of said indicating-plate and rigidly secured thereto and adapted to embrace the adjacent edge of said transparent piece.

3. A display-box provided with a plurality of openings in a wall thereof, an indicating-plate adapted to close one of said openings, a transparent piece adapted to close the other opening and ears intermediate of the adjacent edges of said piece and plate for interlocking the same, said ears being composed of rigid members on said plate and freely embracing opposite faces of said piece.

4. A display-box provided with a plurality of openings in a wall thereof, an indicating-plate or member adapted to close one of said openings, a transparent piece or member adapted to close the other opening, guiding and retaining devices on the interior of the box for said members, and means intermediate of the adjacent edges of said members for locking the same, said means consisting of vertically-arranged ears fixed to the edge of one member and adapted to embrace the adjacent edge of the other member.

GEORGE H. CLIFF.

CHARLES H. W. CLIFF.
